UNITED STATES PATENT OFFICE.

HIRAM N. J. MANSFIELD, OF MALONE, NEW YORK.

MACHINE FOR GRINDING MILL-ROLLERS.

SPECIFICATION forming part of Letters Patent No. 426,192, dated April 22, 1890.

Application filed June 1, 1889. Serial No. 312,861. (No model.)

To all whom it may concern:

Be it known that I, HIRAM N. J. MANSFIELD, a citizen of the United States, residing at Malone, in the county of Franklin and State of New York, have invented a new and useful Machine for Grinding Mill-Rolls, of which the following is a specification.

This invention relates to machines for grinding the faces of the rollers in calendering-machines, roller-mills, and other places where stacks of metal rolls are employed; and it has for its object to construct a machine which may be mounted detachably upon the roller-frame, and by means of which the rolls may be ground without the expensive and laborious process of detaching them from the frame in which they are mounted.

The invention consists in the improved construction and combination of parts, which will be hereinafter fully described, and particularly pointed out in the claims.

In the drawings hereto annexed, Figure 1 is a front elevation of the roller-frame of a calendering-machine to which my improved roll-grinding machine has been applied in position for operation. Fig. 2 is a side elevation of the roll-grinding machine detached from the roller-frame. Fig. 2^a is a detail sectional view of the stud-bolt 14 and screw-threaded rod 16. Fig. 2^b is a plan view of the same. Fig. 3 is a vertical sectional view taken on the line *z z* of Fig. 1 and showing the grinding-disk in side elevation. Fig. 4 is a perspective view of one of the vertical posts or side beams of the grinder-frame. Fig. 5 is a perspective view of one of the supporting-brackets for the latter. Fig. 6 is a detail side elevation of one of the bearings for the main shaft of the grinding-machine. Figs. 7 and 8 are detail views of the vertically-adjustable brackets which support the grinding mechanism. Figs. 9, 10, 11, 12, 13, 14, and 15 are detail views illustrating the clamping device for holding the rollers steady while being operated upon by the grinding-machine. Fig. 16 is a detail front view of the main shaft of the grinding-machine carrying the grinding-disk and of the screw for adjusting the said grinding-disk. Figs. 17 and 18 are detail sectional views taken on the lines *xx* and *yy* in Fig. 1.

The same numerals refer to the same parts in all the figures of the drawings.

1 1 designate the vertical side beams of the frame, which are provided in the usual manner with bearings for the rolls 2 2.

In the construction of the roller-frame and the arrangement of the rollers no invention is claimed, and it will be understood that my present invention, which relates solely to the grinding mechanism, may be applied to and operate upon a calendering-machine roller-frame of any desired construction, or any other machine having two or more vertically-arranged rolls.

3 3 designate a pair of arms or brackets, which are secured, respectively, at the upper and lower ends of the side beams of the machine-frame by means of screws or clamping-bolts 4. The said arms or brackets are provided at their outer ends with bearings 5 for the upper and lower ends of the vertical beams or posts 6, which constitute the main frame of my improved grinding attachment, and which, being mounted in these bearings, 75 may be readily adjusted axially to assist in the adjustment of the parts of the device to be hereinafter described. The upper and lower ends of the said beams or posts are rounded, as shown at 7, so as to fit in their 80 respective bearings, and the said posts, which are by preference square in cross-section, are provided with vertical longitudinal slots 8, extending nearly through their entire lengths.

9 9 designate a pair of boxes, which are fitted and mounted to slide vertically upon the beams or posts 6, said boxes consisting each of the front and rear sections 10 and 11, which are provided with the laterally-extending ears or lugs 12, connected by means of bolts 13.

14 are stud-bolts extending transversely through the boxes 9 and through the slot 8 in the vertical posts 6. Said stud-bolts are provided within the slots 8 with interiorly-screw-threaded eyes 15, forming nuts that work upon the vertical screw-threaded rods 16, which are located within the vertical beams 6 and have their bearings in the lower ends of the said beams and in brackets 17, mounted upon the upper sides of the upper brackets 3, as will be 100 clearly seen by reference to Figs. 1 and 2 of the drawings. The brackets or standards 17 are

provided on their front sides with boxes or 5 bearings 18 for a shaft 19, which is provided with worms 20, meshing with worm-gears 21, which are mounted loosely upon the screw-threaded shafts 16 near the upper ends of said shafts. The shaft 19 is provided adjacent to the boxes or bearings 18 with collars 22, having set-screws 23, by means of which the said collars may be adjusted upon the shaft 19, so 10 as to prevent undue endwise movement of said shaft. Motion may be imparted to the shaft 19 either by means of hand-wheels 24 at one end thereof or by means of the fixed pulley 25, which is mounted upon its opposite end.

15 26 26 are loose pulleys mounted upon the shaft 19 adjacent to the fixed pulley 25, and straight and crossed belts run from the said pulleys 26 to driving-pulleys arranged upon a suitable shaft. (Not shown in the drawings.)

20 It will be seen that by this mechanism the shaft 19 may be caused to revolve in either direction, one of the driving-belts serving to revolve it in each direction and both of said belts running, when idle, upon the loose pulleys 26 26.

25 The worm-gears 21 are provided at their upper ends with clutch-lugs 27, adapted to engage corresponding clutch-lugs 28 upon the lower ends of clamping-collars 29, adjustable 30 upon the upper ends of the screw-threaded shafts 16 by means of set-screws 30. It will be seen that by rotating the shaft 19 when the worm-gears 21 are connected with the clutches 29, and the latter are fixed upon the 35 screw-threaded shafts, the latter may be rotated in either direction, according to the direction in which the shaft 19 revolves, thus raising or lowering the boxes 9, as the case may be, by means of the stud-bolts 14, extending 40 transversely through said boxes and having the screw-threaded perforations that work upon the shafts 16.

45 The boxes 9 are provided with forwardly-extending cylindrical tubular arms or brackets 31, upon which sleeves 32 are mounted to slide. Said sleeves are provided on their upper sides with boxes or bearings 33, in which is mounted the main shaft 34, which is thus arranged transversely to the roller-frame 50 to which my improved grinding-machine is attached. The said main shaft is preferably made tubular in shape, as shown in the drawings hereto annexed, for the purpose of reducing the weight of the same without materially 55 detracting from the strength. The boxes 33, that form the bearings of the said shaft, are provided with detachable caps 35, secured in position by means of bolts 36, and which may be conveniently removed for the purpose of 60 adjusting or removing the said shaft, as occasion may require.

65 The tubular brackets 31 are provided in their under sides with longitudinal slots 37 to admit of the passage of the shanks 38 of stud-bolts 39, the upper ends of which are provided with screw-threaded eyes 40, working upon screw-threaded shafts 41, that ex-

tend longitudinally through the said tubular brackets and are journaled securely in the inner ends of the latter. The stud-bolts 39 70 extend through openings in the under sides of the sleeves 32, that slide upon the brackets 31, and are provided with nuts 42, by means of which they are secured to the said sleeves. The outer ends of the shafts 41 are provided 75 with miter-gears 43, meshing with pinions 44, which are mounted upon the ends of a shaft 45, which is mounted transversely in suitable bearings 46 upon the front ends of the brackets 31. The pinions 44 are provided with 80 collars 47, having set-screws 48, by means of which they may be secured rigidly upon the shaft 45, and which construction enables either one of said pinions to be loosened temporarily when it shall be desired to operate 85 only one of said pinions for the purpose of adjusting or aligning the parts operated thereby, as may be required.

Collars 49, having set-screws 50, serve to retain the shaft 45 securely in its bearings and 90 to prevent it from moving laterally therein.

The shaft 45 is provided at one end with a hand-wheel 51, by means of which it may be conveniently operated. It will be seen that by rotating the shaft 45 a rotary motion in 95 either direction may be imparted to the shafts 41, which, as stated, are screw-threaded to engage the screw-threaded eyes 40 of the bolts 39, which travel in the slots 37 of the brackets 31, and are permanently connected to the sleeves 32, traveling upon said brackets. The said sleeves may thus by this mechanism be moved in either direction inward or outward upon the brackets 31, together with all the mechanism carried by the said sleeves, and 100 which will now be more fully described.

The shaft 34, journaled in the boxes 33, is provided on diametrically-opposite sides with longitudinal feathers 52, extending nearly along the entire length of said shaft and adapted to be received by the longitudinal grooves 53 of the longitudinally-sliding sleeves 54, the inner sides of which are provided with clamping-disks 55, adapted to be connected by means of bolts or in any suitable manner and to hold the emery-wheel or grinding-disk 56, which is in this manner mounted upon and connected with the main shaft. The latter is provided near one of its ends with the main driving-pulley 57, which may be connected by 110 means of a belt with suitable operating machinery.

58 58 designate collars mounted adjustably upon the main shaft adjacent to the boxes or bearings and serving to hold the said main shaft securely in position against lateral movement.

The boxes 33 of the main shaft or the caps 35 of said boxes are provided with upwardly-extending brackets 59, the upper ends of 115 which have boxes or bearings 60 for the ends of a screw-threaded shaft 61, which is thus mounted revolvably in a position parallel to the main shaft. The screw-threaded shaft 61

has a plain or unthreaded extension 62, the outer end of which is provided with a crank or hand wheel 63, and upon which is mounted a fixed pulley 64 and two loose pulleys 65 65, 5 adjacent to each other. The said loose pulleys are belted to the main shaft by the straight and crossed belts 66 and 67, respectively, and it will thus be seen that by shifting either of said belts onto the fixed pulley 64 the screw-threaded shaft 61 may be caused to revolve in either direction. It will also be observed that the said screw-threaded shaft may, when desired, be operated by means of the crank or hand wheel 63.

15 For the purpose of automatically shifting or shifting the belts 66 and 67 when the machine is in operation, I avail myself of mechanism as follows: 68 designates a transverse rod or bar mounted in suitable boxes or bearings 69 in the position parallel to the screw-threaded shaft 61 and the main shaft. Said rod or bar, which is arranged to slide laterally in its bearings, is provided near one end with the links 70 and 71, encircling, respectively, the belts 66 and 67, and adapted to shift or ship the said belts from their respective loose pulleys onto the intermediate fixed pulley 64, which may thus be caused to rotate in either direction. The sleeves 54 54, 30 traveling upon the main shaft, as herein described, are provided with outwardly-extending arms 72, the outer ends of which have interiorly-screw-threaded eyes or openings 73 for the passage of the screw-threaded shaft 61, by the revolution of which the said arms or brackets carrying the sleeves 54 and the grinding-disk 56 may thus be caused to travel in either direction upon the main shaft. The shipping-bar 68 is provided with collars 74, 35 adjustable by means of set-screws 75. The brackets 72 have arms 76, adapted to engage the said collars 74 when the limit of the movement of the said brackets with their attachments has been reached.

40 45 Additional collars 74^a are arranged upon the rod 68 outside the frame to limit the movement of said rod and to prevent the belts from being slipped off their respective pulleys by a too extensive movement of said rod.

The operation of this part of the machine is as follows: Motion is primarily imparted to the main shaft through the medium of the pulley 57. The collars 74 are then set upon the shipping-bar 68 in such a manner as to regulate the extent of the movement of the sleeves 54, carrying the grinding-disk upon the said main shaft. The shipping-bar is then adjusted in such a manner as to cause one of the belts 66 or 67 to run over the fixed pulley 64. The screw-threaded shaft 61 will thus be caused to revolve, and the brackets 72, carrying the sleeves 54 and the grinding-disk, will be caused to travel longitudinally 55 60 65 upon the shafts 61 and 34, respectively. When the limit of the movement has been reached, the arm 76 of one of the brackets 72 will en-

gage one of the collars 74, thus actuating the shipping-bar, causing it to move laterally in its bearings and to ship or shift the belt, which has been working upon the fixed pulley 64, onto one of the loose pulleys 65 and the belt which has been working upon a loose pulley onto the fixed pulley. The direction of the rotation of the screw-threaded shaft 61 will thus be instantly and automatically reversed, and the brackets 72, with their attachments, be caused to travel in an opposite direction until the arm 76 of the other bracket 72 comes in contact with the collar 74 at the opposite end 80 of the shipping-bar, when the operation is again automatically reversed. This operation continues as long as the machine is in motion or until the shipping-bar is so operated by hand as to place both of the belts 66 85 and 67 in engagement with the loose pulleys 65. The operation of the main shaft having the grinding-disk may then continue, the said grinding-disk remaining stationary upon the main shaft. When the machine is in this position, the grinding-disk 56 may be adjusted laterally by means of the crank or hand wheel 63 upon the screw-threaded shaft 61.

90 For the purpose of holding and steadyng the rolls securely in their frame while being operated upon by my improved grinding mechanism, I avail myself of the clamping device illustrated in detail in Figs. 9 to 15, inclusive, of the drawings. The said clamping device comprises a plate or bracket 77, 95 which is substantially T-shaped, the body of which is provided with openings 78, adapted to receive the hook-bolts 79, by means of which the said plate or bracket is clamped upon the I-beams 80, which form the frame 100 in which the rollers are mounted, substantially as shown in Fig. 10 of the drawings. The vertical portions 81 of the T-shaped brackets 77 are provided with perforations 82 82, near their upper and lower ends, adapted 105 to receive the horizontal bolts or screw-threaded rods 83, the inner ends of which are screwed into the upper and lower ends of the yokes 84. Sliding yokes 85 are adjusted upon the bolts 83, and the yokes 84 and 85 are provided 110 on their inner sides or faces with sockets 86, in which are seated the balls or rollers 87.

In practice the yokes 84 and 85 are arranged upon opposite sides of and in such a 115 manner as to clamp the neck of the roller which is to be operated upon. Nuts 88 are arranged to be tightened up against the plate 77, for the purpose of drawing the bolts 83 with the yoke 84 up tightly against the neck 120 of the roller. The plate or portion 81 of the bracket 77 is provided with a central perforation 89, through which passes a set-bolt 90, adapted to bear against the yoke 85, which is thus likewise forced up against the neck of 125 the roller. Jam-nuts 91 are mounted upon the bolts 83 and 90 adjacent to the plate or bracket 77, for the purpose of retaining the parts in position when adjusted.

One of the clamping devices just described is mounted upon the neck at each end of the roller which is to be operated upon, and which is thus connected firmly with the frame in which it is mounted, thereby rendering it impossible for the said roller to shake or tremble while being operated upon. The friction balls or rollers 86 will adjust themselves in the yokes in which they are seated to the necks of the rollers upon which they are mounted, and it will thus be seen that the clamping devices are equally applicable to rollers of different sizes and diameters and having either straight or inclined necks.

15 The operation and advantages of my improved roller-grinding machine will be readily understood from the foregoing description, taken in connection with the drawings hereto annexed.

20 The grinding mechanism may be conveniently attached to a roller-frame of any size and description by means of the clamps or brackets 33. Usually a number of rollers are mounted vertically in the same frame, 25 and it will be seen that by means of the vertical screw-threaded shafts 16 the boxes 9, with their attachments and carrying the complete grinding mechanism, may be adjusted vertically, so as to bring the grinding-disk 30 into vertical alignment with any one of the rollers which it may be desired to operate upon. This adjustment, it will be seen, may be effected either by hand or by means of suitable power applied through the medium 35 of the pulleys 25 and 26. Shipping mechanism, substantially like that employed in connection with the belts 66 and 67, may be employed for the purpose of shifting or shipping the belts upon the pulleys 25 and 26; but such 40 will not usually be required, and has not therefore been shown in the drawings.

When the machine is first started, the emery-wheel or grinding-disk 56 may be at some distance from the face of the roller which is 45 to be operated upon. After the machine has been started the shaft 45 may be operated by means of the hand-wheel 51, so as to bring the said emery-wheel into contact with the face of the roller with any desired degree of pressure.

50 The grinding-disk may, when desired, be suffered to remain stationary upon the main shaft; or it may, by the mechanism herein described, be caused to reciprocate upon the said shaft, thus bringing the said emery-wheel or grinding-disk into contact with the face of the roller for the entire length of the latter; or, when desired, the lateral movement of the grinding-disk may be limited to any desired 55 extent, as may, for instance, be required, when the face of the roller is to be ground out of the true cylindrical shape.

60 The construction of the machine is such that it may be easily and conveniently applied to or detached from the frame the rollers of which are to be operated upon.

Several of the more important and expen-

sive parts of the machine—such as the screw-threaded shafts—are removable and interchangeable, so that they may be changed 70 from one machine to another, as will be found very useful in large mills where more than one grinding-machine is used.

75 The general construction of my improved roll-grinding machine is simple and inexpensive, and by its use the rolls may be ground without being detached from the frame in which they are mounted, this being usually an important item of expense.

80 By means of the clamping device herein described the rolls may be held securely and steadily while being operated upon, and a true and smooth face is thus assured by the use of my improved grinding-machine and its attachments.

85 While I have herein described the preferred form of my invention, I would have it understood that numerous changes in the detail construction might be made without affecting the successful operation of the machine 90 in the least, and I reserve the privilege of making any such changes and modifications as may be resorted to without departing from the spirit of my invention.

Having thus described my invention, what 95 I claim, and desire to secure by Letters Patent, is—

1. The combination, with a roller-frame having a set of rollers mounted permanently therein, of a grinding-machine and means for mounting the same detachably upon the said frame, and a clamping device adapted to connect the rollers with the frame in which they are mounted and to hold them steady during the operation of the grinding mechanism, substantially as set forth.

2. In a roll-grinding machine, the combination, with brackets adapted to be connected detachably to a roller-frame, of vertical beams or supports adapted to be mounted in said brackets and having vertical slots formed therein, the boxes arranged to slide vertically upon said beams or supports, said boxes carrying the grinding mechanism and provided with transverse stud-bolts extending through the slots in the vertical beams or supports and having interiorly-screw-threaded eyes, the vertical screw-threaded shafts extending through the beams or supports, engaging the screw-threaded eyes in the stud-bolts of the vertically-adjustable boxes, and having bearings in brackets or standards extending upwardly from the upper supporting-brackets, worm-wheels mounted loosely upon the said screws, a transverse shaft having worms meshing with the said worm-wheels, mechanism for operating the said shaft, and means for connecting the said worm-wheels rigidly with the screws, upon which they are respectively mounted, substantially as set forth.

3. In a roll-grinding machine, the combination, with a frame having vertical side beams or standards, and brackets supporting said standards and adapted to be connected

detachably to the frame in which the rolls are permanently mounted, of the boxes arranged to slide vertically upon the side beams, the screw-threaded vertical shafts engaging 5 transverse stud-bolts in the said boxes, worm-wheels mounted loosely upon the upper ends of said shafts and having upwardly-extending clutch-lugs, clamps arranged upon said screw-threaded shafts above said worm-wheels and 10 having set-screws by means of which they may be secured rigidly thereon, and downwardly-extending lugs adapted to engage those of the worm-wheels, a transversely-arranged shaft having worms engaging the said 15 worm-wheels, and mechanism for operating the said shaft in either direction, substantially as and for the purpose set forth.

4. In a roll-grinding machine, the combination of vertical side beams or standards, 20 brackets supporting said standards and adapted to be connected detachably to the frame in which the rolls to be ground are permanently mounted, boxes arranged vertically adjustably upon the said side beams and 25 having forwardly-extending brackets, sleeves mounted longitudinally adjustably upon the said brackets, a main shaft journaled in boxes or bearings upon the said sleeves, and an emery-wheel or grinding-disk mounted adjustably upon the said shaft, substantially as 30 and for the purpose set forth.

5. In a roll-grinding machine, the combination of the vertical side beams or standards, the boxes arranged to slide vertically upon the 35 same and having forwardly-extending tubular arms or brackets, the sleeves arranged to slide upon said brackets, grinding mechanism mounted on said sleeves, the stud-bolts extending through longitudinal slots in the said 40 brackets and connected rigidly with the longitudinally-sliding sleeves, suitably-mounted screw-threaded shafts extending through screw-threaded eyes in the said stud-bolts and having pinions at their front ends, and a 45 transverse shaft having miter-gears meshing with said pinions and provided at one end with a hand-wheel by means of which it may be manipulated, substantially as set forth.

6. In a roll-grinding machine, the combination, with the boxes adjustable vertically 50 upon suitable side beams or supports and having forwardly-extending brackets, of the sleeves adjustable longitudinally upon said brackets, the main shaft mounted in suitable 55 bearings upon said sleeves, a pair of sleeves or collars arranged to slide upon the said shaft and having spline or grooves adapted to engage longitudinal keys or feathers in the said shaft, and provided with outwardly-extending 60 brackets having transverse screw-threaded eyes or openings, an emery-wheel or grinding-disk clamped between said sliding sleeves or collars, a transverse screw-threaded shaft extending through the screw-threaded 65 eyes or openings in the outwardly-extending brackets of said sleeves, and mechanism for imparting the rotary motion in either direc-

tion to the said screw-threaded shaft, substantially as set forth.

7. In a roll-grinding machine, the combination of the vertical side beams, the boxes mounted adjustably upon the same and having forwardly-extending brackets, the sleeves sliding longitudinally upon said brackets, the main shaft mounted in bearings upon 70 said sleeves, the collars sliding longitudinally upon said shaft, an emery-wheel or grinding-disk, brackets extending outwardly from said collars and having transverse screw-threaded eyes or openings, a transverse screw-threaded 75 shaft extending through and engaging said openings, and mechanism for imparting rotary motion to the said screw-threaded shaft and means for automatically reversing the direction of its rotation, substantially as 80 herein set forth.

8. In a roll-grinding machine, the combination of the vertical side pieces or supports, the vertically-adjustable boxes upon said side beams, having forwardly-extending brackets, 90 the sleeves mounted adjustably upon said brackets, the main shaft journaled in suitable bearings upon said sleeves, the collars feathered upon said shaft, sliding longitudinally thereon and having outwardly-extending 95 brackets provided with transverse screw-threaded eyes or openings, an emery-wheel or grinding-disk mounted between said collars, arms extending from the latter and adapted to engage collars upon the shipping-bar of the belt-shifting mechanism, the transverse screw-threaded shaft extending through 100 and engaging said screw-threaded eyes or openings and having a fixed pulley and two loose pulleys adjacent thereto, a straight and 105 a crossed belt connecting said pulleys with the main shaft, a transversely-arranged shipping-bar mounted to slide laterally in suitable bearings and having links encircling the said belts, and collars mounted adjustably 110 upon the said shipping-bar, substantially as herein set forth.

9. In a roll-grinding machine, the combination of vertical beams or standards, brackets supporting said standards and adapted to 115 be connected detachably to the frame in which the rolls to be ground are permanently mounted, boxes arranged to slide vertically upon said beams or standards, mechanism for adjusting said boxes and for retaining them 120 in any position to which they may be adjusted, sleeves arranged to slide upon brackets extending forwardly from said vertically-adjustable boxes, the main shaft mounted in bearings upon said sleeves, the grinding-disk 125 arranged to slide laterally upon said main shaft, and mechanism for operating the said grinding-disk and for automatically reversing the direction of its lateral movement upon 130 said main shaft, substantially as herein set forth.

10. The combination, with the herein-described roll-grinding machine, of a roller-frame, a clamping device comprising a pair

of yokes adapted to encircle the neck of the roll which is to be operated upon, and mechanism for clamping the said yokes upon the said roll and for connecting them rigidly with the frame in which the roll is mounted, substantially as and for the purpose herein set forth.

11. The combination of the roller-frame, a T-shaped plate or bracket having suitable perforations, hooked bolts connecting the said plate detachably with the roll-frame yokes adapted to encircle the neck of the roll to be operated upon and having suitable recesses or sockets, friction rollers or balls seated in

the said sockets, and bolts and nuts connecting the said yokes together and clamping them upon the neck of the roll and connecting them rigidly with the plate or bracket attached to the roll-frame, substantially as and for the purpose set forth.

In testimony that I claim the foregoing as my own I have hereto affixed my signature in presence of two witnesses.

HIRAM N. J. MANSFIELD.
